CLAIM

The ornamental design for a stuffer for an electrical wire connector, as shown and described.

DESCRIPTION

FIG. 1 is a right front perspective view of a stuffer according to our new design;

FIG. 2 is a slightly enlarged right front perspective view of the stuffer of FIG. 1;

FIG. 3 is a left side elevation view of the stuffer of FIG. 2;

FIG. 4 is a right side elevation view of the stuffer of FIG. 2;

FIG. 5 is a front elevation view of the stuffer of FIG. 2;

FIG. 6 is a rear elevation view of the stuffer of FIG. 2; and,

FIG. 7 is a top plan view of the stuffer of FIG. 2.

The broken lines in the drawings depict environmental structure, which forms no part of the claimed design.
